(57) **CLAIM**

The ornamental design for a wall-box electrical vehicle charger, as shown and described.

DESCRIPTION

FIG. 1 is a front elevation view of a wall-box electrical vehicle charger;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view of a wall-box electrical vehicle charger.

The broken lines in the drawings are for the purpose of illustrating portions of the article that form no part of the claimed design.

1 Claim, 7 Drawing Sheets
